DESIGN FOR A FIRE-PLACE LINING.

Design No. 14,039, dated July 3, 1883.

UNITED STATES PATENT OFFICE.

JOSEPH A. READ, OF PHILADELPHIA, PA., ASSIGNOR TO GILBERT COMBS,
JOHN BAWDEN, AND JOHN H. BAWDEN, ALL OF FREEHOLD, N. J.

DESIGN FOR A FIRE-PLACE LINING.

SPECIFICATION forming part of Design No. 14,039, dated July 3, 1883.

Application filed May 5, 1883. Term of patent 14 years.

To all whom it may concern:

Be it known that I, JOSEPH A. READ, a citizen of the United States, and a resident of Philadelphia, Pennsylvania, have invented or 5 produced a new and original Design for a Fire-Place Lining, of which the following is a specification.

My design for a fire-place lining is fully shown in the accompanying photographs.

10 The design comprises both the back plate and side plates. The back plate, Figure 1, has a central urn and ornamentation principally of a scroll-like character, and comprising conventionalized representations of stems, leaves, and flowers. Two of the scrolls terminate in 15 dragons' heads, and on each side of the central urn is a figure resembling the fabled cockatrice. The side panels (shown in Fig. 2) have scroll

ornamentation of the same general character as that of the back plate; but these panels have 20 no urn or side figures.

I claim—

1. The design for the back plate, said design comprising the scroll ornamentation, urn, and side figures, as shown and described. 25

2. The design for the side plates, said design comprising the scroll ornamentation, as shown and described.

In testimony whereof I have signed my name to this specification in the presence of two sub- 30 scribing witnesses.

JOSEPH A. READ.
